MATTHEW R. HULL AND ROLAND H. MONEY, OF CONNERSVILLE, INDIANA, ASSIGNEES
TO REX MANUFACTURING COMPANY, OF CONNERSVILLE, INDIANA, A CORPORA-
TION OF INDIANA.

AUTOMOBILE WINDOW.

Application filed October 21, 1925. Serial No. 63,988.

Our invention relates to a window for automobiles having closed bodies and a principal object of the invention is to provide a window by which ventilation can be effected with great efficiency. In the use of closed cars it has been found that there is considerable difficulty in procuring satisfactory ventilation without causing disagreeable drafts of cold air and without admitting rain or snow in bad weather. Our invention provides a window which does away to a great extent with the difficulties heretofore experienced and which may be opened or closed with a minimum of difficulty and inconvenience.

Referring to the accompanying drawings which are made a part hereof and on which similar reference characters indicate similar parts,

20 Figure 1 is a side elevation of our device in position on an automobile body,

Figure 2, a transverse section, and

Figure 3, a detail of a part shown in Figure 1.

25 In the drawings reference character 10 indicates a window frame forming a part of the body of the vehicle which window frame may be of any conventional or desirable construction. The window 11 is provided with

30 a suitable frame 12 along one side and the bottom, which frame may if desired extend all the way about the window and which in this instance consists of a strip of sheet metal U-shaped in cross section, this sheet

35 metal being bent about the edge of the glass.

An ear 13 is struck up at one edge of the sheet metal at the bottom of the window to provide a convenient hand grip. A rod 14 is enclosed by the sheet metal 12 at the forward edge of the window and said rod is pivoted in the upper and lower members of the window frame. A rockarm 15 is secured to the rod below the lower member in any convenient way and said rockarm is pivotally connected by a rivet 17 or otherwise to a link 16 which in turn is attached to a spring 18 secured to the window frame by a bracket 19 having a hook 20 engaging a coil of the spring.

50 As will readily be understood from consideration of Figures 2 and 3 the spring 18 is a double-acting one holding the window

either in open or closed position, this by reason of the fact that the hook 20 which forms the point of attachment of the spring, 55 the lower end of rod 14 and the pivot 17 are normally out of line, the pivot 17 being free to move to one side or the other of a line connecting the points 14 and 20. When the window is pushed outward it will take 60 the position indicated in dotted lines at 21 while the rockarm 15 and the link 16 will assume the positions indicated in dotted lines in Fig. 3. Contrariwise when the window is closed the parts will swing to the position indicated in full lines. The various parts cooperating to open and close the window may be so proportioned that the window can be very easily opened and closed.

When the window is open a very considerable draft of air will enter the body of the car and this will travel substantially in a forward direction but will be broken up and distributed so as not to be unduly violent and thus will not cause discomfort to 75 the occupants of the car.

It will be obvious to those skilled in the art that various changes may be made in our device without departing from the spirit of the invention and therefore we do not limit 80 ourselves to what is shown in the drawings and described in the specification but only as indicated in the appended claims.

Having thus fully described our said invention which we claim as new and desire 85 to secure by Letters Patent, is:

1. The combination in an automobile of a window casing, a window frame in said window casing, a rod non-rotatably connected to said window frame and projecting into 90 said casing for supporting the window frame, a link non-rotatably connected to said rod with its free end swingable in an arc, a second link connected to the free end of the first mentioned link, and a spring 95 connected to said second link for holding the window in opened or closed position, substantially as set forth.

2. The combination in an automobile of a window casing by means of a window frame mounted in said window casing, a rod non-rotatably connected to said window frame and projecting into said casing at one end and through the casing at the other

end, a link non-rotatably connected to the last mentioned end of said rod with its free end swingable in an arc, a second link connected to the free end of the first mentioned link, and a spring connected to said second link for holding the window in opened or closed position, substantially as set forth.

In witness whereof, we have hereunto set our hands at Connersville, Indiana, this 15th day of October, A. D. nineteen hundred and twenty-five.

MATTHEW R. HULL.
ROLAND H. MONEY.
